DOOR LATCH

Ralph R. Teetor, Hagerstown, Ind.

Application January 10, 1951, Serial No. 205,320

9 Claims. (Cl. 292—64)

2

The invention relates generally to door latches and more particularly to a door latch which may be of such construction that it may be operated by pushing or pulling on a knob.

The general object of the invention is to provide a novel door latch of the foregoing general character, which operates smoothly with only a small effort on the part of the person opening or closing the door, and which holds the door firmly closed against accidental release.

Another important object is to provide a novel door latch of the foregoing general character, in which the latch is releasable by a relatively small movement of the knob in the direction of opening of the door.

A further object is to provide a novel door latch having a catch engageable with a keeper in the door frame to hold the door closed and in which very little force is required to actuate the catch upon closing of the door, so that latching of the door when it is swung toward its closed position is assured.

Still another object is to provide a novel door latching means which is made of relatively simple, easily manufactured parts and which requires a very simple mortise in the door in order to install the latch.

Other objects and advantages will become apparent from the following description taken in connection with the accompanying drawings in which:

Fig. 1 is a longitudinal sectional view of a door latch embodying the features of the invention and showing the latch in position in a door and in engagement with a keeper mounted in the door frame.

Fig. 2 is a longitudinal sectional view taken along the line 2—2 of Fig. 1.

Fig. 3 is a transverse sectional view taken on the line 3—3 of Fig. 1.

Fig. 4 is a view similar to Fig. 1 but showing the door as it is being swung open.

Fig. 5 is a view similar to Figs. 1 and 4 but showing the door as it is being closed.

A door latch in accordance with the invention is adapted for a wide variety of uses in connection with hinged doors of various types. In the present instance it is illustrated in a form adapted for ordinary doors of a house, for example. The latch includes a manually operable means for releasing it, and the invention is of such scope that said means may be of various types but is herein illustrated as of the push-pull type rather than utilizing a rotatable member as in the case of ordinary door latches. The manually operable member of the door latch may also be embodied in various forms but is herein illustrated as a simple knob.

Broadly, the invention contemplates a door latch comprising a casing adapted to be secured to the door and enclosing catch means comprising a pair of movable members, one of which is adapted to engage a keeper mounted in the door frame in latching relation thereto. The two members are conjointly movable by engagement of the one member with the keeper on opening the door, and the one member is movable alone by engagement with the keeper on closing the door. Coacting with the catch means and particularly with the other of the two members is a manually operable member which is engageable with said other member to hold it against such conjoint movement to prevent opening of the door, and is releasable therefrom to permit such opening. The present door latch also includes a spring means tending to hold the two members against conjoint movement as well as to hold the one member against movement rela-

tive to the other, and also tending to hold the manually operable member against release.

For purposes of illustration, the embodiment of the invention shown in the drawings is adapted for use in a door indicated at 10, the door being mounted within a frame 11 provided with a stop 12. The frame 11 is mortised to receive a keeper 13 in the form of a plate mounted flush with the frame and having an aperture 14 for receiving the engaging portion of the latch. While a latch embodying the features of the invention may be made in various forms for various types of mounting on the door 10, in the present instance, it is illustrated as being mounted in a mortise 15 extending inwardly from the edge of the door.

As heretofore stated, the latch includes a casing, indicated at 16, which preferably is in the form of a generally rectangular tube formed from sheet metal. Thus, the mortise 15 is merely a simple hole of generally rectangular form corresponding to the cross-sectional shape of the casing 16. At the outer end of the casing 16, there is secured a face plate 17 which extends beyond the casing 16 on all four sides thereof. A shallow mortise, of course, is cut in the edge of the door 10 to receive such face plate.

Within the casing are mounted catch means comprising two coacting movable members, one of which is adapted to engage the keeper 13 in latching relation thereto. This one member is hereinafter referred to as a catch and is indicated generally at 20. The catch 20 is of substantially segmental shape provided with an arcuate outer surface 21, and is adapted to extend through the aperture 14 with the arcuate surface 21 engaging one edge of the aperture.

The other member, referred to above, is a carrier for the catch 20 in the form of a slide indicated generally at 22 and mounted in the casing for reciprocatory movement longitudinally thereof. The slide 22 carries the catch 20 with the latter pivotally mounted on the slide, so that the two may move conjointly.

In such conjoint movement, the slide is movable longitudinally of the casing 16 while the catch 20 pivots on the slide. To support the catch 20 for such pivotal movement, the slide at its outer end is provided with a pair of laterally spaced ears 23 between which a narrowed portion 24 of the catch is positioned, the portion 24 and the ears 23 being secured together by a pivot pin 25. To facilitate the reciprocatory movement of the slide 22, a pair of rollers 26 (see Fig. 3) are mounted on the pivot pin 25 between the ears 23 and engage the adjacent face of the casing 16 in rolling relation thereto.

The slide 22 comprises a pair of elongated side bars 27 extending inwardly of the casing 16, the outer ends of the bars constituting the ears 23. Adjacent the outer end of the slide, the bars 27 are integrally connected by a transverse bridge portion 30. Thus, the slide 22 is supported in its reciprocatory movement by engagement of the bars 27 with the adjacent wall of the casing, while the outer ends are supported by the rollers 26 so that the slide may move inwardly and outwardly of the casing free without any tendency to bind therein.

The position of the parts when the door is closed and the catch 20 is in engagement with the keeper 13 is shown in Fig. 1, and the position of the parts of the device as the door is being opened is shown in Fig. 4. From these two figures, it will be noted that by movement of the door in the opening direction, the engagement of the keeper 13 with the arcuate surface 21 of the catch 20 causes a camming action on the latter, tending to turn it in one direction about its pivot 13, and at the same time such force applied to the catch 20 tends to push the slide 22 inwardly of the casing, carrying the catch 20 with it. Thus, the catch 20 and the slide 22 will be moved to the position shown in Fig. 4 conjointly so that the arcuate surface 21 of the catch will clear the keeper 13 and permit the door to open. To facilitate the camming action of the keeper 13 on the catch, the engaging edge of the aperture 14 in the keeper is beveled as at 31. After the door is swung clear of its frame, the slide 22 and the catch 20 will be swung to the position shown in Fig. 1 by spring means which will hereinafter be described.

On closing the door, only the catch 20 is moved but

such movement is in the opposite direction from that occurring on opening the door. As illustrated in Fig. 5, the catch 20 is provided with a curved surface 32 extending from adjacent the pivot pin 25 outwardly to intersect with the arcuate surface 21. As the door is closed, with the catch 20 extending outwardly from the edge of the door, the curved surface 32 engages the edge of the door frame and by continued closing movement, such engagement results in a camming action, swinging the catch 20 about the pivot pin 25 inwardly of the door, the slide 22 remaining stationary during such movement. When the door is fully closed, the catch 20 is forced outwardly into the aperture 14 in the keeper by the spring means hereinbefore referred to. To prevent the catch 20 from projecting beyond the outer end of the casing more than the desired amount, the catch is provided with a pair of lugs 33 extending from the two side faces thereof and engageable with inwardly extending portions 34 formed on the face plate 17.

The invention also includes manually operable means for preventing the catch 20 from being disengaged from the keeper 13 except when desired. Preferably such manually operable means coacts with the slide 22 to prevent inward movement thereof and in the present instance constitutes a latch indicated generally at 35. The latch 35 has a generally L shape with one arm, indicated at 36, lying between the side bars 27 of the slide 22. The latch 35 is supported for pivotal movement by a pin 37 extending crosswise of the casing 16 and located in the other arm of the L. Such other arm is bifurcated to provide two portions 40. When the latch is in holding engagement with the slide, it is slightly tilted as illustrated in Figs. 1 and 5, and the one arm 36 engages the inner edge of the bridge portion 30 of the slide so as to prevent inward movement of the latter. Outward movement of the slide is limited by engagement of the ears 23 with the ends of the portions 34 on the face plate 17. Thus, when the latch 35 is tilted so that the arm 36 engages the bridge portion 30 of the slide, movement of the latter is prevented, but when the latch 35 is turned about its pivot 37 to move the end of the arm 36 out of engagement with the bridge portion 30, as illustrated in Fig. 4, the slide may be moved inwardly to permit release of the catch 20 from the keeper. The pivot pin 37 is so positioned relative to the wall of the casing on which the slide 22 moves, that the bars 27 of the slide are held against tilting away from the wall. The fact that the surfaces 21 and 32 of the catch 20 slant toward each other and away from the planes of the respective sides of the casing 16 permits the catch to swing in both directions from its intermediate position without jamming against the casing.

The latch 35 may be manually released from the slide 22 by means which may be embodied in various forms but is here illustrated as comprising knobs mounted on either side of the door and adapted to be pushed or pulled, depending upon which knob is grasped, in the same direction as the opening movement of the door. To release the latch 35, a pair of forked arms 41 extend inwardly of the casing from the bifurcated portions 40 of the latch. The forked arms 41 embrace a tubular member 42 extending transversely within the inner end of the casing 16 and in the tubular member or sleeve is mounted a rod 43 slidably supported for movement axially thereof. The rod 43 at its ends is provided with reduced threaded portions 46 to receive the parts to be grasped, which in the present instance are illustrated as knobs 47.

To provide for installation of the rod 43 and the tubular member in the door after the casing 16 has been inserted into its mortise, the tube 42 and the rod 43 are together inserted transversely through an aperture 50 (see Fig. 1) at one side of the door and extending into the mortise 15. The aperture 50 and a corresponding aperture 51 in the adjacent side of the casing 16 are made of sufficient diameter to permit passage therethrough of a pair of flanges 52 formed on the sleeve 42. An aperture 53 in the opposite side of the casing and a corresponding aperture 54 through the door at said opposite side are of smaller diameter than the flanges 52 so that the flange adjacent the aperture 53 will engage the adjacent wall of the casing to prevent movement of the sleeve beyond that position. When the sleeve is so located, an escutcheon 55 is threaded on to the sleeve and abuts the adjacent face of the door to hold the sleeve

in position in the casing. A corresponding escutcheon 56 is threaded on the sleeve 42 on the first-mentioned side of the door. The rod 43 between its two reduced threaded portions 46 is somewhat longer than the sleeve 42 so that the rod may be moved endwise in the sleeve to release the latch 35.

As heretofore mentioned, the device includes spring means tending to hold the catch 20 in keeper-engaging position. The spring means also tends to shift the slide 22 to its outward position, to swing the latch 35 into engagement with the keeper 22, and to move the knobs 47 with the rod 43 into position ready for actuation to release the latch 35. Preferably such spring means comprises a unitary device, indicated generally at 60, for performing all these functions. This device includes a coil spring 61 coacting at one end with one of the movable parts of the device and at its other end with other of the movable parts thereof. Thus, in the present instance, the spring 61 is mounted on a spring supporting member comprising a rod 62 having a head 63 formed at one end and pivotally connected by a pin 64 to the catch 20. To receive the head 63, the catch 20 is notched at 65 and the pin 64 is supported in the portions of the catch on either side of the notch. The head 63 is of larger size than the rod 62 so as to provide a shoulder against which the end of the spring 61 may abut.

The other end of the spring 61 is adapted to engage the bifurcated portions 40 of the latch 35. To this end, a pin 66 extends between the bifurcated portions 40 and is received in a slot 67 formed in the adjacent end of the rod 62. Thus, the adjacent end of the spring 61 bears against the bifurcated portions 40.

With this construction of the spring means, the pressure of the spring 61 against the head 63 tends to swing the catch 20 outwardly of the casing about its pivot 25 so that it will engage in the aperture 14 of the keeper 13 when the door is in proper position. The same pressure of the spring 61 acting against the catch 20 also tends to move the slide 22 to its outward position, the catch 20 being held against further outward movement by the lugs 33 engaging the portions 34 on the face plate 17 and the ears 23 on the slide likewise engaging such portions to limit the outward movement of the slide. The pressure of the spring 61 at its other end against the bifurcated portions 40 of the latch 35 tends to swing the latter about its pivot 37 so that it will engage the bridge portion 30 of the slide 22 when the latter is in its outward position, thus holding the slide against inward movement and consequently preventing the conjoint movement of the slide and the catch 20 necessary to open the door. Such swinging movement of the latch 35 by the spring 61 causes the forked arms 41 of the latch to shift the rod 43 to the proper position for manual actuation by either of the knobs 47 when it is desired to release the catch.

It will be noted from an inspection of Fig. 1 that the direction of movement of the knobs 47 and the rod 43 necessary to release the latch 35 from the slide 22 is in the direction of swinging movement of the door on opening. Thus, by pushing or pulling on one or the other of the knobs in the normal direction of opening the door, the catch 20 will be released for release of the door. When the knobs 47 are pushed in the opposite direction to close the door, no movement of the rod 43 relative to the door occurs and the latch 35 remains in engagement with the slide 22 so that the latter cannot move. However, the camming action of the door frame against the curved surface 32 of the catch 20 causes the latter to swing inwardly of the casing relative to the slide 22 without movement of the latter. The catch 20 thus is free to pass by the door frame and the keeper until the door is fully closed, at which time the spring 61 swings the catch 20 into the aperture 14 in the keeper.

It will be apparent from the foregoing description that the device will operate smoothly since the catch 20 may easily swing in opposite directions from its latch-engaging position, on opening or closing the door. When the conjoint movement of the latch 20 and the slide 22 occurs on opening the door, the slide is readily movable within the casing because the outer end of the slide is supported by the rollers 26 which prevent binding of the slide in the casing. When the door is fully closed, the spring 61 holds the catch 20 firmly in an engagement with the keeper to avoid accidental release of the door. In order to release the catch and permit the door to be

swung open, only a relatively small movement of the knobs 47 is required and only a small force is needed to swing the latch 35. When the door is swung closed, the catch 20 swings easily to the position shown in Fig. 5 so that the door does not have to be slammed shut in order to cause the catch to engage with keeper. The parts of the device are all relatively simple and may be easily manufactured and only a simple mortise is required in the door to install the latch.

I claim:

1. Door latching means comprising means comprising a catch adapted to extend outwardly of the edge of the door for latching engagement with a keeper, said catch being pivotally supported for movement in both directions from an intermediate keeper-engaging position, said catch also being supported to move bodily inwardly of the door when pivoted in one direction, means pivotally supporting said catch and movable therewith when the catch is moved bodily inward, a manually releasable latch for holding said catch against movement bodily inwardly of the door, and spring means interposed between said catch and said latch and tending to return said latch to catch-holding position and to return said catch to said intermediate position.

2. Door latching means comprising means comprising a catch adapted to extend outwardly of the edge of the door for latching engagement with a keeper, said catch being pivotally supported for movement in both directions from an intermediate keeper-engaging position, said catch also being supported to move bodily inwardly of the door when pivoted in one direction a manually releasable latch for holding the catch against bodily inward movement, and a spring device having one end engaging said catch to hold the latter in latching position and having its other end engaging said latch and tending to hold it against release.

3. Door latching means comprising means comprising, a catch adapted to extend outwardly of the edge of the door for latching engagement with a keeper, said catch being pivotally supported for movement in both directions from an intermediate keeper-engaging position, said catch being adapted to move bodily inwardly of the door when pivoted in one direction, a manually releasable latch for holding said catch against bodily inward movement, a spring-supporting member having one end pivotally connected to said catch and having its other end in sliding engagement with said latch, and a coiled spring extending about said member and bearing at one end against said one end of said member and at its other end against said latch.

4. Door latching means comprising a tubular casing adapted to fit within a mortise extending inwardly from the edge of the door, a slide supported by said casing for sliding movement inwardly of the casing, a catch pivotally supported on said slide in the outer end of said casing and extending therefrom for latching engagement with a keeper, said catch being swingable in both directions from an intermediate keeper-engaging position and being adapted to move inwardly of the casing with the slide swung in one direction and to permit the slide to remain stationary when swung in the other direction, a latch pivotally supported in said casing and engageable with said slide to hold it against movement, a spring device engaging both said catch and said latch and resisting movement thereof, and manually operable means for swinging said latch out of engagement with said slide.

5. Door latching means comprising a tubular casing adapted to fit within a mortise extending inwardly from the edge of the door, a slide supported by said casing for sliding movement inwardly of the casing, a catch pivotally supported on said slide in the outer end of said casing and extending therefrom for latching engagement with a keeper, said catch being swingable in both directions from an intermediate keeper-engaging position and being adapted to move inwardly of the casing with the slide when swung in one direction and to permit the slide to remain stationary when swung in the other direction, a latch for holding said slide against movement and pivotally supported in said casing, said latch having a laterally extending portion, a spring device engaging said catch and said portion of the latch and tending to move said latch into engagement with said slide, and manually operable means extending into said casing for swinging said latch out of engagement with said slide.

6. Door latching means comprising a tubular casing

85

of generally rectangular cross-section and adapted to fit within a mortise extending inwardly from the edge of the door, a slide mounted in said casing and slideable along one side wall of said casing, a catch extending from the outer end of said casing for latching engagement with a keeper, a pin pivotally supporting said catch on said slide, said catch being swingable in both directions from an intermediate keeper-engaging position and being adapted to move the slide inwardly when swung in one direction and to permit the slide to remain stationary when swung in the other direction, a pair of rollers mounted on said pin in rolling engagement with said side wall to facilitate movement of the slide, and a manually releasable latch mounted in said casing and engageable with the slide to hold it against movement.

7. Door latching means comprising a tubular casing of generally rectangular cross-section and adapted to fit within a mortise extending inwardly from the edge of the door, an elongated slide in said casing extending along one side wall thereof and movable longitudinally of said casing, a catch pivotally supported on the outer end of the slide and extending from the outer end of the casing for latching engagement with a keeper, said catch being swingable in both directions from an intermediate keeper-engaging position and being adapted to move the slide inwardly when swung in one direction and to permit the slide to remain stationary when swung in the other direction, the inner end of said slide having a longitudinally extending slot, a latch pivotally supported in said casing and extending into said slot for engaging the slide to hold it against movement, and a manually operable member extending into said casing and engaging said latch for releasing it from said slide.

8. Door latching means comprising a tubular casing adapted to fit within a mortise extending inwardly from the edge of the door, a slide supported by said casing for sliding movement inwardly of the casing, a catch pivotally supported on said slide in the outer end of said casing and extending therefrom for latching engagement with a keeper, said catch being swingable in both directions from an intermediate keeper-engaging position and being adapted to move inwardly of the casing with the slide when swung in one direction and to permit the slide to remain stationary when swung in the other direction, a latch pivoted in said casing and engageable with the slide to hold it against movement, and a manually operable rod extending through the casing transversely thereof and engaging said latch to swing it out of engagement with said slide.

9. Door latching means comprising a tubular casing adapted to fit within a mortise extending inwardly from the edge of the door, a slide supported by said casing for sliding movement inwardly of the casing, a catch pivotally supported on said slide in the outer end of said casing and extending therefrom for latching engagement with a keeper, said catch being swingable in both directions from an intermediate keeper-engaging position and being adapted to move inwardly of the casing with the slide when swung in one direction and to permit the slide to remain stationary when swung in the other direction, a latch pivoted intermediate its ends in said casing and having one end engageable with the slide to hold it against movement, the other end of the latch being forked, a tubular member adapted to extend through the door and extending transversely through the casing and through the forked end of said latch, escutcheon plates secured to the ends of said tubular member for holding it in place, and a manually operable rod slidably mounted in said tubular member and having a cross pin extending through slots in said tubular member and engaging the forked end of said latch for swinging the latter out of engagement with said slide.
